UNITED STATES PATENT OFFICE

ELMER W. ZWIEBEL, OF LOS ANGELES, CALIFORNIA

DESIGN FOR A RADIOCABINET

Application filed October 8, 1930. Serial No. 37,180. Term of patent 3½ years.

To all whom it may concern:

Be it known that I, ELMER W. ZWIEBEL, a citizen of the United States, residing at Los Angeles, in the county of Los Angeles and State of California, have invented a new, original, and ornamental Design for Radiocabinets, of which the following is a specification, reference being had to the accompanying drawing, forming part thereof.

Fig. 1 is a front elevational view of a radio cabinet showing my new design.

Fig. 2 is a side elevational view of the cabinet.

I claim:

The ornamental design for a radio cabinet as shown.

ELMER W. ZWIEBEL.
